US0D1002719S

(12) **United States Design Patent** (10) **Patent No.:** **US D1,002,719 S**
(45) **Date of Patent:** **** Oct. 24, 2023**

(54) **TRANSACTION CARD**

- (71) Applicant: **Apple Inc.**, Cupertino, CA (US)
- (72) Inventors: **Teofila Connor**, San Francisco, CA (US); **Peter Russell-Clarke**, San Francisco, CA (US); **Christopher I. Wilson**, San Francisco, CA (US)
- (73) Assignee: **Apple Inc.**, Cupertino, CA (US)
- (**) Term: **15 Years**
- (21) Appl. No.: **29/802,847**
- (22) Filed: **Aug. 9, 2021**

Related U.S. Application Data

- (63) Continuation of application No. 29/682,950, filed on Mar. 8, 2019, now Pat. No. Des. 927,590.
